UNITED STATES PATENT OFFICE.

HARRY LESTON DAUGHERTY, OF CARSON CITY, NEVADA.

ROSETTE FOR BRIDLES AND OTHER PARTS OF HARNESS.

1,345,076.

Specification of Letters Patent. Patented June 29, 1920.

Application filed September 16, 1919. Serial No. 324,125.

To all whom it may concern:

Be it known that I, HARRY L. DAUGHERTY, a citizen of the United States, and a resident of Carson City, in the county of 5 Ormsby and State of Nevada, have invented certain new and useful Improvements in Rosettes for Bridles and other Parts of Harness, of which the following is a specification.

10 My invention is an improvement in rosettes for bridles and other parts of harness, and has for its object to simplify and cheapen the construction thereof and at the same time to render the same strong, durable and attractive.

15 In the drawings:

Figure 1 is a perspective view of the head stall and brow band of a bridle provided with the improved rosette;

20 Fig. 2 is a plan view of the rosette, with parts broken away;

Fig. 3 is a side view of the rosette looking from the inner side.

25 As is known, on riding bridles where a rosette is used there is a buckle also, and the object of the present invention is to combine the rosette and buckle into a single construction.

30 The head stall 1 of the bridle is connected to the brow band 2 by means of the rosettes. Each of these rosettes consists of a hollow body 3 of suitable size, outline and suitably 35 ornamented, the rosettes in the present instance being plain spherical segments.

Each rosette has connected with the flat 40 side thereof a keeper 4, and to this keeper the ends of the head stall 1 are secured as shown in Fig. 1. Upon each keeper there is pivotally and slidably mounted a latch bar

45 Each of these latch bars has a longitudinally extending slot 6 which engages the body of the keeper, and at the opposite end each bar has an angular portion 7, and the angular portion of each latch bar has a locking extension 8 in the opposite direction from the body of the latch bar.

The head stall has a series of alined slots 9 through which the angular portion 7 of the latch bar is adapted to pass, as shown in Fig. 1, and to engage within an opening 10 in the flat side of the rosette. As shown in Figs. 1 and 2, when the extension 8 is engaged with an opening 9 and the slot of the rosette, and is moved longitudinally to

cause the extension 8 to engage beneath the 55 flat side of the rosette, the rosette will be locked to the head stall. The brow band has an opening at each end adapted to register with one of the openings of the adjacent series of openings 9 of the head stall 60 for receiving the angular end of the latch bar, and it will be evident that the latch bar, in addition to connecting the rosette to the head stall, also connects the brow band to the head stall and to the rosette. Thus 65 with a single article, which may be considered either as a buckle or as a rosette, the double function of buckle and rosette is served.

70 While the rosette is shown in connection with the browband of the bridle, it is applicable for use in any other connection, as, for instance, at the chin strap or in any other position.

75 I claim:

1. In a bridle, the combination with the head stall and the brow band, of a rosette having means for connecting the brow band to the head stall and for connecting the rosette to said brow band and head stall, said 80 means comprising a keeper on the rosette through which the end of the head stall is passed, a latch bar pivoted on the keeper and mounted to slide transversely thereof, the rosette having an opening and the latch 85 bar an angular portion provided with a locking extension adapted to pass within the opening and to engage within the rosette, the brow band and head stall having openings through which the angular portion of the latch bar passes to engage the 90 rosette.

2. A rosette for bridles comprising a hollow body having an inner flat wall provided with a transverse slot and with a keeper adjacent to the slot, a latch bar having a slideable connection with the keeper and having an angular portion adapted to enter the slot and to engage the inner face of the flat wall to hold the latch bar in place.

3. A rosette having a slot and a latch bar connected to the rosette is spaced relation and movable longitudinally of the slot, and having an angular portion adapted to enter the slot and to engage within the 105 rosette.

HARRY LESTON DAUGHERTY.
